UNITED STATES PATENT OFFICE.

STOYAN V. TSANOFF, OF NEW YORK, N. Y.

MOLD FOR CEMENT BLOCKS.

No. 877,874.

Specification of Letters Patent.

Patented Jan. 28, 1908.

Application filed February 7, 1907. Serial No. 356,212.

To all whom it may concern:

Be it known that I, STOYAN V. TSANOFF, a citizen of the United States, residing in the city, county, and State of New York, have 5 invented certain new and useful Improvements in Molds for Cement Blocks, of which the following is a specification.

This invention relates to the class of molds or machines employed for making building 10 blocks from cement by what is known as the "wet process", as distinguished from the dry or pressing process. It may be explained that in the wet process of making cement blocks, the material, in a relatively thin or 15 liquid condition, is poured into the open mold and allowed to "set" and solidify, while in the other or "dry" process the material, in a thick but plastic mass, is put into the mold and pressed to solidify and compact 20 it. The blocks molded are usually of an oblong rectangular shape and each has extending through it two passages or flues of which the axes are vertical when the block is laid. The flues are so disposed in the block that 25 when the blocks are laid in the wall the passages in the superposed blocks register so as to form continuous air-flues.

The present invention relates in part to the 30 general construction of the mold whereby economy is attained and a corrugated surface is imparted to the non-exposed faces of the block; in part to the construction of the cores which form the flues in the block, and in part to the construction which facilitates 35 the molding of a plurality of blocks simultaneously.

In the accompanying drawings, which illustrate embodiments of the invention—Figure 1 is a perspective view of a part of the 40 mold, the section being taken substantially at line x^1 in Fig. 3. Fig. 2 is a transverse section of the mold, taken through a core, at line x^2 in Fig. 3. Fig. 3 is a plan of the mold. Fig. 4 is a perspective view of the molded 45 block; and Fig. 5 is a transverse section of the block through one of the flues therein. Figs. 6, 7 and 8 illustrate the multiple form of the mold. Fig. 6 is a perspective view; Fig. 7 is a longitudinal, vertical section, and 50 Fig. 8 is a plan. Fig. 9 is a perspective view of a back differing slightly from that shown in Fig. 4. This will be hereinafter described.

The single mold is illustrated in Figs. 1, 2 and 3. In these figures a, a , designate the two 55 sides of the mold; b, b , are the two ends, and c the bottom plate. These will be made, pref-

erably, of corrugated sheet-iron. The bottom plate may be secured to a bottom-board d , and this board be supported on bars B .

The sides a and ends b are secured together 60 at the corners by similar or like devices seen clearly in Figs. 1 and 3. This device may consist of an elbow hasp e , hinged to one part and engaging a staple f on the other part, and a pin g (Fig. 1), engaging said staple, in 65 any known way, to hold the hasp in place. The cores are formed as clearly shown in the drawings. On one side a is fixed a section h of the core; this section is tapered a little, made hollow from sheet-metal and open at 70 its smaller end. On the opposite side a is fixed a section h^1 , which is longer than the section h and smaller at its inner end so that when the sides a are in place the section h^1 will enter and fit snugly in the section h so as to prevent 75 leakage of the thin material from which the block is molded. It will be noted that the core-sections on the opposite sides will be made to register and that they will be secured rigidly to the respective sides a of the 80 mold so that they cannot yield.

In order to provide horizontal air-passages 85 in the wall, connecting with the flues F , the block has in its upper and lower faces channels i , (Figs. 4 and 5) and these are formed by metal plates j secured to the sides a in any suitable manner. They are shown (in Fig. 1) as riveted.

In the operation of molding the block, the parts of the mold are set up as in Fig. 3, and 90 the sides a secured to the ends b . The material is now poured in until the mold is full, and the surface (which is to form the exposed face of the block), is smoothed with a suitable tool. After the block has solidified sufficiently, the mold is opened; this is effected 95 by drawing out the pins g , disengaging the hasps e , and removing the ends b . The sides a are now removed in such a way as to draw out the core-sections h and h^1 from the 100 block. This is facilitated by the taper of the sections. The block now rests on the bottom plate c , and it may be moved to any point desired by sliding the plate and block onto a suitable wheeled carriage. There will, 105 or may be any number of bottom plates c for and with each mold. The corrugated metal imparts its form to all the faces of the block with which it comes in contact, and these corrugations aid in securing the blocks together with cement.

Where it is desired to combine a plurality

of molds in a group so that a number of blocks may be molded simultaneously, the construction seen in Figs. 6, 7 and 8 is employed. In this construction the sides a , a' are at the ends of the elongated group of molds, and are substantially the same as the sides a in the single mold; but the intermediate sides or partitions a^1 are slightly different. The end-pieces b^1 are elongated, each 10 serving as an end for all of the molds M in the group. There is a separate bottom plate c for each mold (Fig. 7), and the intermediate sides a^1 extend down between the bottom plates of adjacent molds in the group. 15 These sides a^1 are held in place at their upper edges by providing each with an apertured lug k at each end, said lug engaging a slot in the upper edge of the end-piece b^1 , and providing hooks m on the latter to engage the 20 apertures in the respective lugs. Each intermediate side a^1 carries core-sections fixed on both of its faces. The operation of molding with this group of molds may be as follows. The mold being set up as in the 25 drawings, the semi-liquid material is poured into all of the molds in the group, and smoothed as before described. When the material has solidified sufficiently, the parts of the mold are disengaged and the end- 30 pieces b^1 removed. The side a at one end of the group is now removed as explained with reference to the operation of the single mold. The bottom plate with the end-block thereon is now drawn out in such a manner as to 35 disengage the block from the core-sections on the first intermediate side a^1 . This first block is now removed and the same procedure then employed with the others.

It should be borne in mind that the conditions are not the same in molding such 40 blocks by the "wet" process, as in the "dry" or pressure process. In the latter process fixed and interlocking core-sections cannot be used with success; and in the wet process 45 less stiffness and strength of the materials will serve.

The telescoping and interlocking core-sections need not be entirely hollow; but if 50 made solid of wood, it is preferred to cover them with sheet-metal. The point is to provide a cheap mold made up of separable parts, but it will be obvious that if the pin g be left in the staple at one side, the side and end of the mold will remain hinged together, 55 as they may be, the hasp serving as a hinge.

The corrugations may be disposed in any

way desired; that is, they may run in one direction on a part of the mold and in another direction in another part thereof. By 60 smoothing the face of the molded block is merely meant that it is finished as desired with a suitable tool.

The block shown in Fig. 9 illustrates several slight variations from the block seen in Fig. 4. For example the flues F are set 65 nearer to the outer face of the block than to the inner face thereof. This is sometimes desirable. Also, the channels i extending throughout the entire length of the block are omitted and recesses i' substituted. These 70 are to receive the fingers in lifting the block. Respecting the molds in the group, this invention is not limited to the mold-ends or end-pieces b^1 being all in one piece. Obviously the several mold-ends might be each a 75 separate part.

Having thus described my invention, I claim—

1. A mold of the character described comprising a bottom, upright sides and ends extended above the bottom and having separable connections, and tapered core sections held upon opposite sides of the mold, one of said core sections being hollow and having its smaller end of larger diameter than the 80 smaller end of the other core section, and adapted, when the parts are in relation, to receive the smaller end of said other core section.

2. A mold of the character described comprising a bottom, upright sides and ends extended above the bottom and having separable connections, partitions extended parallel to the sides and separably connected with the ends and spaced from the sides and 90 from each other, and aligned tapered core sections held upon the sides and upon opposite faces of the partitions, one of each two adjacent core sections being hollow and having its smaller end of greater diameter than 95 the smaller end of the adjacent core section and adapted, when the parts are in relation, to receive the smaller end of said adjacent core section.

In witness whereof I have hereunto signed 100 my name this 31st day of January 1907, in the presence of two subscribing witnesses.

STOYAN V. TSANOFF.
